H. D. GUE.
METHOD OF SEPARATING GASES.
APPLICATION FILED DEC. 11, 1913.

1,123,867.

Patented Jan. 5, 1915.

UNITED STATES PATENT OFFICE.

HARRY D. GUE, OF NEW YORK, N. Y.

METHOD OF SEPARATING GASES.

1,123,867.

Specification of Letters Patent.

Patented Jan. 5, 1915.

Application filed December 11, 1913. Serial No. 805,977.

To all whom it may concern:

Be it known that I, HARRY D. GUE, a citizen of the United States, residing at New York, in the county of New York and State 5 of New York, have invented certain new and useful Improvements in Methods of Separating Gases, of which the following is a specification.

My invention relates to a certain new and 10 improved method of separating gases of different densities or specific gravities, such for instance as oxygen and nitrogen of the atmosphere. By my improved method I obtain a better separation of the gases than 15 has heretofore been possible and at the same time operate cheaper and more rapidly.

My improved method consists in forming the mixed gases into a vortex, revolving the vortex at a high velocity, supplying the 20 mixed gases to the vortex at a high velocity and withdrawing the separated gases from the vortex.

In the accompanying drawing I have shown a central vertical section of one form 25 of apparatus by means of which my method may be carried out.

In the machine illustrated, 5 designates a base and 6 a stationary casing mounted on the base. The top of the casing is formed 30 into a chamber 7 from which leads the outlet pipe 8. The bottom of the chamber is formed with a downwardly projecting lip 9, forming a mouth 10 opening into the chamber. The inner surface of the top of the 35 casing is curved as shown at 11, and the curve extends over the outer surface of the lip as shown. Extending from one side of the curved portion 11 is a second outlet pipe 12.

40 13 designates a bowl carried by a shaft 14 mounted at its lower end in the bearing 15, and provided with a pulley 16 by means of which it may be driven at a very high speed to give the bowl a peripheral speed of 45 approximately 1000 feet per second. The

bowl is shown as cone shaped but this is not essential and may be varied as desired.

The mixed gases are introduced into the bowl through the pipe 17, which is shown as extending through the chamber 7 and down 50 close to the bottom of the bowl where it is provided with the outwardly extending branches 18 terminating in expansion nozzles 19, through which the mixed gases to be separated are delivered under such pressure in the pipe 17 as to give the gases as 55 they are delivered from the nozzles, substantially the velocity of the peripheral speed of the bowl.

From the foregoing description of the 60 construction of the machine illustrated it will be seen that there will be a vortex of the gases formed within the bowl and that the mixed gases will be delivered to this vortex at a very high velocity and this 65 velocity will be substantially maintained for the entire time the gases are in the vortex, due to the speed of rotation of the bowl. The heavier gases will thus be separated from the lighter gases and the former taken 70 away through the delivery pipe 12, while the latter pass through the pipe 8.

What I claim as new and desire to secure by Letters Patent is:

The method of separating gases of different densities which consists in forming the 75 mixed gases into a vortex, revolving said vortex at great velocity, supplying the mixture to the vortex at substantially the velocity of the vortex and removing the heavier 80 gases from the peripheral portion of the vortex and the lighter gases from the central portion thereof.

In testimony whereof I affix my signature in presence of two witnesses.

HARRY D. GUE.

Witnesses:

SAMUEL WELLS,
L. SCHENCK.
